UNITED STATES PATENT OFFICE

SALVATORE RESCA, OF BROOKLYN, NEW YORK

SASH HOLDER

Application filed April 19, 1930. Serial No. 445,629.

The present invention relates to improvements in window sash-holders by the use of which the counterbalancing weights and their flexible connections are dispensed with.

5 The main object of the invention is to provide a sash-holder which is simple in construction, efficient in operation, durable in use and capable of manufacture on a commercial scale, or in other words one which 10 is not so difficult to produce as to be beyond the reasonable cost of such a contrivance.

Another object of the invention is to provide a sash-holder of the type mentioned which may be readily applied to windows 15 without necessitating material changes in the construction of the later.

With these and other objects in view, which will more fully appear as the nature of the invention is better understood, the same consists in the combination, arrangement and construction of parts hereinafter described, pointed out in the appended claim and illustrated in the accompanying drawing, it being understood that many changes may be made 20 in the size and proportion of the several parts and details of construction within the scope of the appended claim, without departing from the spirit or sacrificing any of the advantages of the invention.

25 30 One of the many possible embodiments of the invention is illustrated in the accompanying drawing, in which:—

Figure 1 is a front elevation of a window having the invention applied thereto, the 35 same being partly in section; Fig. 2 is a vertical section taken through a window frame provided with the improvement, the sashes being removed in order to more clearly show the construction; Fig. 3 is a section 40 taken on line 3—3 of Fig. 1, on a larger scale; and Fig. 4 is a section taken on line 4—4 of Fig. 3.

In the drawing the numeral 10 indicates a window frame of ordinary construction, provided on its jambs with guide strips 11 for the 45 sashes 12. Between each pair of guide strips is counter-sunk into the window jamb a channel-rail 13, extending throughout the length of the jamb and having rotatably mounted therein rollers 14 which revolve on

horizontally disposed spindles 15 and are closely spaced, as shown in the several figures of the drawing. The rollers are flush with the exposed faces of the jambs and contact with the stiles 16 of the window sashes, thereby guiding the latter in their movement and preventing rattling thereof. In each stile of each sash is formed a mortise 17, in which is disposed a casing 18 held therein by screws 19, or otherwise. In each casing are slidably arranged two spring-actuated bolts 20, provided with reduced ends 21 which project through apertures 22 in the casing toward the adjacent rollers 14. Each set of bolts is so spaced that it is adapted to project between two pairs of rollers, as clearly shown in Fig. 4 of the drawing. The outer ends of the bolts are properly rounded, so that they ride smoothly over the rollers in the up and down movement of the sashes but project sufficiently between the rollers to maintain the sashes in any desired position without the aid of the usual counter-weights.

The operation of the device is simple and will be readily understood from the foregoing 75 description. It is obvious that the sashes may be raised and lowered without manually actuating the bolts, the latter sliding back and forth automatically in their casings as the sashes are being moved in either direction. 80 In this manner the construction herein described differs from the usual rack-bar and latch-bolt type devices, wherein the sashes may be raised without actuating the bolts manually but can be lowered only after the 85 bolts have been manually disengaged from the rack-bars.

What I claim is:—

The combination with a window frame, of a slideable sash therein, a plurality of spaced 90 rollers on the jambs of said frame in contact with the stiles of said sash, thereby providing a rolling contact between said stiles and said jambs for guiding said sash in its movement and preventing rattling thereof, a casing 95 on each stile of said sash, and a plurality of spring-actuated bolts slidably arranged in each casing for co-operation with said rollers, said bolts being also spaced and adapted to ride over said rollers as the sash moves in 100

said frame and project between the rollers to maintain the sash in adjusted positions on said frame.

Signed at New York city, in the county of New York, and State of New York, this 17th day of April, A. D. 1930.
